UNITED STATES PATENT OFFICE.

MARTIN MILLER AND HARRY WEISS, OF PHILADELPHIA, PENNSYLVANIA.

SIGN.

Application filed October 8, 1923. Serial No. 667,106.

To all whom it may concern:

Be it known that we, MARTIN MILLER and HARRY WEISS, citizens of the United States, residing at Philadelphia, in the county of 5 Philadelphia and State of Pennsylvania, have invented certain new and useful Improvements in Signs, of which the following is a specification.

Our invention relates to that type of sign 10 in which a series of plates of suitably opaque material apertured to represent letters, numerals, or the like are disposed with reference to suitable illuminating means; such apertured plates being preferably associated 15 with transparent or translucent sheets through which sufficient illumination may be transmitted to clearly show the letter defined. By placing the light transmitting sheets behind the apertured plates, our improved sign is available for day and night 20 use.

Our improved sign may be in the form of a hollow shell or frame, made of any suitable material, and in the present instance 25 we have illustrated the same as providing two rows of plate receiving openings. It will be understood that a greater or less number of rows of openings may be provided as may be desired without departing 30 from our invention.

An important object of our invention is to provide a structure which shall be water-proof, and to so arrange the light transmitting sheets and the apertured plates as to 35 shed rain water and prevent the same entering the frame or shell of the improved sign structure.

A further object of our invention is to 40 provide simple and efficient means for retaining the apertured plates and light transmitting sheets in place, and a still further object is to provide a sign of the described type in which the apertured plates may be quickly inserted or removed, and without 45 disturbing the light transmitting sheets.

These and other features of our invention are more fully set forth hereinafter, reference being had to the accompanying drawings, in which:

50 Figure 1, is a front elevation of a portion of a sign constructed in accordance with our invention.

Fig. 2, is a cross-sectional view on the line 2—2, Fig. 1, and

Fig. 3, is a sectional plan view on the line 55 3—3, Fig. 1.

In constructing our improved sign, we may provide a hollow frame 10, having inner and outer marginal flanges 11, with a recessed portion 12 between such flanges in 60 which may be placed, at more or less regular intervals, a series of electric lamps 13.

We have shown in the drawings and will describe a structure having two rows of 65 sign letters, numerals, characters or the like, but it is obvious that a single row may be employed in which the arrangement of the parts making up the same may be like that of the upper or lower row as illustrated in Figs. 1 and 2, of the drawings, and that 70 more than two rows, in which the arrangement of parts may be like those illustrated may also be employed, without departing from our invention.

Mounted within the body of the sign 75 frame and extending longitudinally of the same in the present instance, are a series of horizontal partitions, 15, 15^a, 15^b and 15^c, which may be secured to the rear wall of the structure and extend to the front of the 80 same. The forward edges of these partitions may be flanged as indicated at 16, 16^a, 16^b and 16^c, and such flanged portions provide, in connection with a series of vertical 85 division strips 17 and 17^a, which may be disposed at regular intervals, spaces or openings to receive separate plates 18, which are apertured to indicate letters, numerals, or other characters that may be employed to 90 make up a display sign.

The flanged portion 16 of the upper partition 15, projects slightly forward of the inner marginal flange 11 of the frame, and has a portion 19 which overhangs the vertical division strips 17; the flanged portion 95 16^a of the partition 15^a, forms a shelf at the front of the structure upon which the apertured plates 18 of the upper row may rest, and its forward edge is turned down, as indicated at 19^a, to overhang the flanged portion 16^b of the partition 15^b and the upper ends of the division strips 17^a, and the flanged portion 16^c of the partition 15^c, also serves as a shelf to support the apertured plates 18 of the lower row.

100 The vertical division strips 17 and 17^a are inclined forwardly from top to bottom, and their lower ends terminate substantially op-

posite the shelves formed by the flanged portions of the partitions 15^a and 15^c. The lower ends of the vertical division strips 17 and 17^a may be covered by horizontal division strips 20 and 20^a which, with the overhanging portions 19 and 19^a of the partitions 15 and 15^b, frame the spaces receiving the apertured plates comprising the sign.

Behind the vertical division strips 17 and 17^a, we provide a second set of vertical supports, indicated at 21, each of which carries a flat spring member 22, and between said springs and the rear faces of the vertical division strips 17 or 17^a, we dispose sheets 18^a of a light transmitting body; transparent or translucent glass, for instance, which may be illuminated by lamps disposed within the body of the frame, those indicated at 23 and 23^a, for instance, which may be supported by the horizontal partitions 15^a and 15^c.

The horizontal division strips 20 and 20^a are disposed over the lower ends of the vertical division strips 17 and 17^a, forward of the front of the frame, so as to provide spaces, indicated at 24, through which the light transmitting sheets and the apertured plates may be inserted or removed; the lower part of Figs. 1 and 2, illustrating the manner of inserting or removing said apertured plates, and the upper part of said views showing the manner in which said apertured plates and the light transmitting sheets are held in place upon the shelves of the horizontal partitions 15^a and 15^c. For the purpose of retaining these plates and sheets in place, we provide the shelves with retaining lips 25, disposed opposite each opening; the said sheets and plates being pressed against said lips by the spring members 22.

In order that the light transmitting sheets 18^a may be held against edgewise movement, and prevented from being lifted over the lips 25 when removing or inserting the apertured plates 18, we provide a stop which may be in the form of a screw 25^a, inserted in the overhanging portions 19 or 19^a, and overlying the top edge of said sheets 18^a, as clearly illustrated in the drawings.

The overhanging portions 19 and 19^a project beyond the face of the sign structure proper so that any moisture falling upon the same will be shed away from the body of the sign structure, and any rain or moisture which strikes the face of the apertured plates, or the light transmitting sheets behind the same, will be diverted and will pass through the spaces 24 behind the horizontal strips 20 and 20^a through which said plates and sheets are inserted or removed, and fall away from the sign.

By reason of our improved construction, the sign structure is completely water-proof, and all danger of rain-water or other mois-

ture entering the interior of the same and affecting the electrical connections is avoided. As may be understood, it is a simple matter to lift any one of the apertured plates clear of its retaining lip 25 and remove the same; the tension of the springs 19 being sufficient to hold the parts in position but not sufficient to prevent easy removal or insertion of the apertured plates. In like manner the light transmitting plates 75 may be inserted or removed.

The term "light-transmitting" used in the appended claims is intended to cover any form of transparent or translucent plates employed, and the term "apertured plate" is 80 intended to cover the removable sign element, whether the aperture thereof indicates a letter, numeral, or any character which may be employed in making up a display sign.

We claim:

1. In a sign, a frame having an opening, a support behind said opening, an apertured plate disposed in said opening and resting on said support; the latter being spaced 90 from said frame to provide an opening through which said apertured plate may be inserted to rest on said support, and means for retaining said apertured plate in position.

2. In a sign, a frame having an opening, a support behind said opening and spaced from the lower portion of the same, an apertured plate insertible from the bottom 100 of the frame through said space, and a lip carried by said support behind which said plate may rest.

3. In a sign, a frame having a series of openings, apertured plates disposed behind said openings, supporting means for said plates spaced from the front of the frame at the lower part of said openings whereby said plates may be inserted from the bottom, and a series of lips for retaining such plates in position.

4. In a sign, a frame having an opening, a support behind said opening and spaced from the lower portion of the same, an apertured plate insertible from the bottom of the frame through said space, a lip carried by said support behind which said plate may rest, and tension means for pressing the plate against said lip.

5. In an illuminated sign, the combination of a frame having a series of plate-receiving spaces formed therein, supports disposed behind said spaces, means for illuminating said spaces, light transmitting sheets disposed in said spaces, apertured plates disposed in front of said light transmitting sheets; said frame providing openings forwardly of the supports through which said plates and sheets may be inserted, and means for retaining said plates and sheets in position on said supports.

6. In an illuminated sign, the combination of a frame having a series of plate-receiving spaces formed therein, means for illuminating said spaces, a series of light transmitting sheets and a series of apertured plates disposed in said spaces, supports for said sheets and plates; said frame having a division strip in front of said support and forming the lower portion of said 10 plate receiving spaces and said division strip being spaced from the support to permit insertion of said sheets and plates from beneath, lips for retaining said plates and sheets in position, and spring means for 15 pressing the plates and sheets against said lips.

7. In a sign, a frame having an opening, a support behind said opening and spaced from the lower portion of the same, a series 20 of plates or sheets insertible from the bottom of the frame through said space, a lip carried by said support behind which said

plates may rest, and means for preventing edgewise movement of one of said plates after it has been positioned. 25

8. In an illuminated sign, the combination of a frame having a series of plate-receiving spaces formed therein, supports disposed behind said spaces, means for illuminating said spaces, light transmitting sheets disposed in said spaces, apertured plates disposed in front of said light transmitting sheets; said frame providing openings forwardly of the supports through which said plates and sheets may be inserted, means for retaining said plates and sheets in position, and means for preventing upward movement of said sheets when inserting or removing the apertured plates. 30 35

In testimony whereof we affix our signatures hereto. 40

MARTIN MILLER.
HARRY WEISS.
